UNITED STATES PATENT OFFICE.

DAVID AUER, OF MILAN, MISSOURI.

GRAPPLE.

SPECIFICATION forming part of Letters Patent No. 795,089, dated July 18, 1905.

Application filed April 19, 1905. Serial No. 256,344.

To all whom it may concern:

Be it known that I, DAVID AUER, a citizen of the United States, residing at Milan, in the county of Sullivan and State of Missouri, have 5 invented new and useful Improvements in Grapples, of which the following is a specification.

My invention relates to grapples; and it consists of certain novel features of construction hereinafter described and claimed.

The invention is more particularly designed for anchoring a snatch-block used for hauling an overturned or derailed railway-car back on the track.

15 The object of the invention is to provide an implement of this kind which will securely grip the rail and which can be readily applied at any point on the rail.

In the accompanying drawings, Figure 1 is 20 a side elevation, and Fig. 2 a top plan view, of the invention. Fig. 3 is a front end view.

Referring specifically to the drawings, the grapple comprises two members 5 and 6, respectively, which are connected by a pivot or 25 hinge 7. These two members have a substantially semicircular form and at their free ends each has a shank 8. At their outer ends the shanks are formed with jaws to grasp the rails, said jaws being recessed, as at 9, in 30 which the head of the rail 10 fits. The portions 11 below the recesses are constructed to grip the web of the rail. The jaws are clamped on the rail by a link 12, which has a portion

13 arranged to be placed around the shanks 8 of the grapple. The opposite sides of the 35 part 13 are made slightly tapering, as shown, so that a pull on the link causes the jaws by reason of the wedge action of the part 13 to tightly grip the rail. The snatch-block 14 is hooked on the link 12. The link is sufficiently 40 large to accommodate a number of such, if necessary.

The device is simple and strong and can be readily applied at any point on a rail, and it is reliable and efficient in operation. The 45 jaws are applied to and detached from the rail by opening them, which can be readily done by removing the link 12.

Having thus described my invention, what is claimed as new, and desired to be secured 50 by Letters Patent, is—

A grapple comprising two members which are pivotally connected; shanks extending from the free ends of said members, and provided with gripping-jaws; a link having a 55 tapering portion extending around the shanks; and hauling means secured to the link.

In testimony whereof I have signed my name to this specification in the presence of 60 two subscribing witnesses.

DAVID AUER.
